UNITED STATES PATENT OFFICE.

FRANKLIN HUBBARD BELLOWS, OF WORCESTER, MASSACHUSETTS, ASSIGNOR TO WALDEN-WORCESTER, INCORPORATED, OF WORCESTER, MASSACHUSETTS, A CORPORATION OF MASSACHUSETTS.

METHOD OF ATTACHING A TOOL HEAD TO ITS HANDLE.

Application filed August 9, 1922. Serial No. 580,624.

To all whom it may concern:

Be it known that I, FRANKLIN HUBBARD BELLOWS, a citizen of the United States, residing at Worcester, county of Worcester, and State of Massachusetts, have invented certain new and useful Improvements in the Methods of Attaching a Tool Head to Its Handle, of which the following is a specification.

10 This invention relates to a method of attaching a tool head to its handle and more particularly to an improved method of constructing a cross-handled socket wrench having the socket member permanently secured 15 to the handle in such manner as to prevent relative movement when in use.

The objects of my invention are to provide an improved form of cross, or T handle, for tools, more especially an improved form 20 of handle for those wrenches used to engage automobile wheel demountable rim securing bolts or nuts, which will have a portion for one handed "speed" operation enabling "spinning" of the work when it is easy to 25 turn, together with portions having greater leverage adapted for two handed operation when greater power is of aid in turning the work, which will effect an appreciable saving in the material, time and expense necessary to the process of manufacture, which improved handle can be secured into the working member as it is formed to the improved handle shape without employing other parts than the working member and the handle, thus greatly reducing the cost 30 and time of manufacture while providing a handle which is of strong durable construction and of such shape as to be used to better advantage than the present forms.

40 The present common methods of forming the cross handle and securing the socket member of a cross handle socket wrench to its cross handle, is to form the steel rod or heavy wire used for the handle into a T 45 shape by first bending a section of rod at right angles to a shank portion then doubling back the greater part of the said section upon the lesser part so that the doubled back part extends over and beyond the 50 shank portion a distance equal to the length of the lesser part. The vertical or shank part of this handle is then secured to the socket portion by inserting its end into a hole in the base of the socket then drilling a

hole transversely through both the base of 55 the socket and the handle, a pin being driven through said hole and riveted therein so as to prevent turning of the handle in the socket and to hold the socket firmly upon the handle. This method and construction involves 60 an unnecessary amount of material, time and expense much of which is eliminated by my method of construction.

The accompanying drawings and description will serve to show one embodiment of 65 my invention as applied to socket wrenches.

In the accompanying drawings like numerals indicate the same parts throughout the several views;

Figure 1 is a side elevation of the improved form of socket wrench embodying my invention, with the socket member shown in vertical section;

Figure 2 is a sectional elevation with parts broken away showing a simplified method 75 of securing the improved handle in the socket member;

Figure 3 is a plan view taken from Figure 1, looking at the recess end of the socket member.

In the specific embodiment of the invention illustrated by the drawings, the numeral 4 indicates my improved form of handle. Located at the middle of this handle is the metal socket member 6 with a socket 85 recess 8 for engaging a nut, or the like, which is to be turned.

Generally the handle 4 is formed of a solid metal rod or heavy wire bent to the required shape. I bend the ends which protrude from the metal socket member 6 to substantially the shape shown so that the portions 5-5 adapted for gripping in the hands, for power operation, are raised from the working plane of the socket member 6 90 and the hands of the operator are protected from injury due to contact therewith while still working to advantage for the purpose of turning the socket member 6 with the nut, or the like, which the socket member has 95 engaged in its socket recess 8. It will be seen that these portions 5-5 are so separated from each other, by the depressed portion which carries the socket member, that for fast operation, when little power is required, the operator's hand may conveniently grasp the socket member itself, or the portions of handle directly adjacent thereto,

to spin the tool with its engaged work, the portions 5—5 exerting a flywheel effect to aid such spinning.

For the purpose of engaging the handle 4 the socket member 6 has an opening 7 which is slightly larger than the handle 4 to permit the insertion of the handle before it is bent to the improved shape. After inserting the handle 4 in the socket member 6 the ends of the handle 4 are bent in a press or other suitable power machine, or may be held in a vise and bent manually to my improved shape.

Parts of the socket member 6 may be then forced into the handle 4 by inserting a punch into the socket recess 8 in the socket member 6, then by exerting force on this punch the relatively thin wall between said socket recess 8 and the handle opening 7 is formed into projections forced into the walls of the handle 4 as at 9, in Figures 1 and 3, this secures the socket member rigidly upon the handle without the addition of pins, bolts, or the like, and without disfiguring the socket member 6.

In Figure 2 is shown my preferred form of engagement between the handle 4 and the socket member 6. The socket member 6 in this case has an aperture 11, on the same axis as socket recess 8 completely through the socket member 6, although it is not essential for the purpose of the invention that the aperture 11 extend entirely through the socket, an aperture 8 separated from the hole 7, by a wall of metal being also utilizable in this embodiment of the invention. The opening 7 for receiving the handle 4, has its axis at right angles to this aperture 11 and cuts through the remaining metal of the socket member 6. Opening 7 is thus divided into two sections 7—7 and the handle 4 passes through one section 7, across the aperture 11, then through the remaining section of the opening 7. The handle 4 is inserted in the socket member 6 and bent, preferably by the methods previously described, the portion of the handle 4 which lies within the aperture 11 is now unsupported, and the forces which bend the portions of the handle exterior to socket member 6, distort that portion of the handle 4 lying within this aperture 11, beyond its elastic limit so that its walls are forced, and permanently set, against the walls of the opening 7 at points 10—10—10—10 binding the metal so tightly together that socket member 6 is securely held against any movement on the handle 4 without other fastening means. Another method of attaching the handle 4 to the socket 6 against relative movement consists in bending or distorting the portion of the handle 4 which lies within the aperture 11, Fig. 2, by pressure applied directly to the said portion through the socket opening either before or after

the bending of the exterior portions or simultaneous therewith.

While I have shown my invention as applied to socket wrenches, it will be evident that it is equally useful for any tool requiring a "cross", or T, shaped handle, or in fact, to any tool requiring a handle which may be bent after insertion in a working member. And although I have shown and described only one embodiment of my invention it will be readily understood that many changes and modifications may be made therein within the scope of the following claims without departing from the spirit and scope of the invention, it being my intention to claim the same broadly in whatever form its principles may be employed.

What I claim is:

1. The method of making a tool comprising forming a tool head having an opening therethrough, positioning a handle in said opening with its end portions extending beyond the surface of the head, and bending said end portions in such manner as to distort the intermediate portion within the opening whereby to restrain movement of the tool head thereon.

2. The method of making a tool comprising forming a tool head having an opening therethrough, positioning a handle in said opening with its end portions extending beyond the surface of the head, and bending said end portions in the same plane whereby to distort the portion of the handle within the opening and restrain movement of the tool head thereon.

3. The method of making a tool comprising forming a tool head having an opening therethrough, positioning a handle in said opening with its end portions extending beyond the surface of the head, and bending said end portions in the same direction whereby to distort the portion of the handle within the opening and restrain movement of the tool head thereon.

4. The method of forming a tool of the class described which comprises providing a wrench socket having a hole extending therethrough at right angles to the axis of the socket, inserting a handle through said hole, bending the handle upwardly adjacent the surface of the socket to distort the portion in the hole and to form portions for one hand operation of the wrench, then bending each upwardly extending end of the wrench outwardly to be in substantially the same axis and parallel to the axis of the hole in the socket to form two handles for the application of increased torque to the socket.

In testimony whereof I have affixed my signature to this specification.
